(57) **CLAIM**

The ornamental design for a directional soccer cleat, as shown and described.

DESCRIPTION

FIG. 1 is a perspective view of a directional soccer cleat, showing my new design;

FIG. 2 is a front elevational view thereof;

FIG. 3 is a side elevational view thereof, the other side being a mirror image thereof;

FIG. 4 is a rear elevational view thereof;

FIG. 5 is a top plan view thereof; and,

FIG. 6 is a bottom plan view thereof.

The broken lines in the Figures are for illustrative purposes only and form no part of the claimed design.
